(74) Attorney, Agent, or Firm — Matthias Scholl P.C.;
Matthias Scholl(57) **CLAIM**

The ornamental design for a pipe brush, as shown and described.

DESCRIPTION

FIG. 1 is a front elevation view of a pipe brush;
 FIG. 2 is a rear elevation view thereof;
 FIG. 3 is a left-side elevation view thereof;
 FIG. 4 is a right-side elevation view thereof;
 FIG. 5 is a top plan view thereof;
 FIG. 6 is a bottom plan view thereof; and,
 FIG. 7 is a perspective view thereof.
 The article is shown with a symbolic break in its length. The appearance of any portion of the article between the break lines forms no part of the claimed design.
